US0D1082605S

(12) **United States Design Patent** (10) **Patent No.:** **US D1,082,605 S**
(45) **Date of Patent:** **** Jul. 8, 2025**

(54) **CINCHING CLIP LINK**

(71) Applicant: **Tara Meissner**, Henderson, NV (US)

(72) Inventor: **Tara Meissner**, Henderson, NV (US)

(73) Assignee: **VERSALINKS HOLDINGS, LLC.**,
Henderson, NV (US)

(**) Term: **15 Years**

(21) Appl. No.: **29/877,081**

(22) Filed: **Jun. 1, 2023**

Related U.S. Application Data

(63) Continuation-in-part of application No. 16/953,996, filed on Nov. 20, 2020, now Pat. No. 11,707,117, which is a continuation-in-part of application No. 15/986,682, filed on May 22, 2018, now abandoned.

(57) **CLAIM**

The ornamental design for a cinching clip link, as shown and described.

DESCRIPTION

FIG. 1 is a front view of a first embodiment of a cinching clip link showing my new design;

FIG. 2 is a back view thereof;

FIG. 3 is a side view thereof, wherein an opposite side view is a mirror image thereof;

FIG. 4 is a top view thereof;

FIG. 5 is a bottom view thereof;

FIG. 6 is a back perspective view thereof; and

FIG. 7 is a front perspective view thereof, showing the cinching clip link in use.

FIG. 8 is a front view of a second embodiment of the cinching clip link;

FIG. 9 is a back view thereof;

FIG. 10 is a side view thereof, wherein an opposite side view is a mirror image thereof;

FIG. 11 is a top view thereof;

FIG. 12 is a bottom view thereof;

FIG. 13 is a back perspective view thereof; and,

FIG. 14 is a front perspective view thereof, showing the cinching clip link in use.

In FIGS. 7 and 14 the broken lines are for environmental purposes only and form no part of the claimed design.
